To all whom it may concern:

Be it known that I, MORTIMER G. The leading feature is the style or design of bedstead shown in the drawing, having the scalloped or shell-shaped ornamental unions or joints a a between the vertical spindles and 15 cross-bars and the same style of scalloped or shell-shaped ornamental unions or joints b on a larger scale between the cross-bars and posts of the bedstead.

What I claim is—
